[57] CLAIM

The ornamental design for a blow molded seat, as shown and
described.

DESCRIPTION

FIG. 1 is a front perspective view of the blow molded seat
showing our new design;

FIG. 2 is a front elevational view thereof;

FIG. 3 is a top plan view thereof;

FIG. 4 is a right side elevational view thereof;

FIG. 5 is a rear elevational view thereof; and,

FIG. 6 is a bottom view thereof.

The left side elevational view is a mirror image of FIG. 4.
